UNITED STATES PATENT OFFICE.

GEORGE L. ANDERS, OF BOSTON, ASSIGNOR TO HIMSELF AND E. B. WELCH, OF CAMBRIDGE, MASSACHUSETTS.

IMPROVEMENT IN DOUBLE-TRANSMITTING PRINTING-TELEGRAPHS.

Specification forming part of Letters Patent No. 120,019, dated October 17, 1871.

To all whom it may concern:

Be it known that I, GEORGE L. ANDERS, of Boston, in the county of Suffolk and State of Massachusetts, have invented certain Improvements in Double-Transmitting Printing-Telegraph Instrument, of which the following is a specification:

Figure 1 is a plan view of an electric printing-telegraph-instrument embodying my invention. Fig. 2 is an elevation of the same.

My invention consists in arranging the parts of a printing-telegraph instrument, and the transmission of electric currents, so as to effect the transmission of two messages simultaneously over one wire; and my invention consists, further, in the arrangement of two printing apparatuses in one instrument, and their magnetic attachment included in one circuit.

Referring to the drawing, *a* is the base of the telegraph-instrument, upon which is placed the permanent magnet *b*; also, electro-magnet *c*, responding to the positive current, and magnet *d* to the negative one, and actuating the levers *e* *e'*, which are pivoted to standard *f*. *h* represents the type-wheel shaft, and *i* the spindle which sets the sliding plate in motion. Both shafts are shown as broken off, but should be connected with the motor-commutator and key-board of a telegraph-machine. The wires *k* *k'* connect the magnets with the ground *G*, and the wires *l* *l'* with the line *L*. The type-wheel *t* is mounted upon shaft *h*, and revolves about the center of the upper platform. The type-wheel is provided, on its periphery, with thirty letters or ciphers, and moves correspondingly and in exact positions to a type-wheel on a like instrument at the distant station. To the upper portion of spindle *i* is secured a crank or eccentric, *n*, which transmits a reciprocating motion to a slide-plate, *o*, in such a manner that for every revolution of the type-wheel the spindle *i* accomplishes thirty revolutions, and therefore thirty double oscillations of slide-plate *o*. There is another sliding plate, *p*, on top of plate *o*, which, when a current is passing through magnets *c* and *d*, is locked with the sliding plate *o*, the length of the stroke, however, being terminated by catches *s* *s'*, pivoted to plate *p*, and when lowered, resting against stops *u* *u'*, and then compelled to follow the motion of sliding plate *o*; but when raised, they become free of said stops. To plate *p* are

attached two presses, *v* *v'*, which hold the paper against the type-wheel, and pins *w* *w'*, which vibrate the bell-crank levers *x* *x'*, to the longer arm of which are fastened feed-plates, when an impression is desired. The catches *s* *s'* are raised or lowered by means of slots, *y* *y'*, and levers, *e* *e'*, as the armatures are attracted or repelled by the currents in the electro-magnets; but while the one is affected only by the positive current, the other is sensitive only to the negative one. *z* *z'* are the paper strips on which the messages are to be imprinted.

A positive electric current is supposed to be transmitted from the distant station, the armature of lever *e* being drawn down and the other end raised, throwing catch *s* from stop *u*, and causing sliding plate *o* to act upon plate *p* so as to throw, by means of pin *w*, bell-crank lever *x* toward one of the presses *v*, and feeding a strip of paper toward the type-wheel, where it is to be held by press *v* to receive the impression of the selected letter. When two of these instruments are suitably connected together, the commutator of one instrument will transmit positive currents and affect the operation of the presses responding to positive currents in both instruments, and the commutator of the other instrument will transmit negative currents and effect the operation of the presses responding to negative currents. Thus all the letters of one message are selected from the type-wheels by negative electric pulsations, and the letters of the other message are selected by currents of a positive polarity.

What I claim as my invention, and desire to secure by Letters Patent, is—

1. The transmission of electrical currents in one circuit, a current in one direction securing the selection and impression or printing of a letter, sign, or character of a telegram; and transmitted in opposite direction, securing the selection and impression of a letter, sign, or character of another and separate telegram, substantially as set forth.

2. The transmission of electric currents transmitted through a circuit, effecting the operation of one or the other of two printing or impression mechanisms, according to the direction of the currents, in a printing-telegraph instrument, substantially as specified.

3. Two impression mechanisms, or their equiv-

alents, attached to one or more type-wheels in a printing-telegraph instrument operating in one circuit, substantially as set forth.

4. The use of two strips of paper, or their equivalent, on a printing-telegraph instrument, substantially as shown and described.

5. The printing of two separate and distinct messages simultaneously, in a printing-telegraph

instrument, by means of one circuit, substantially as set forth.

In testimony whereof I have signed my name to this specification in the presence of two subscribing witnesses.

Witnesses: **GEO. L. ANDERS.**
